UNITED STATES PATENT OFFICE.

ROBERT E. CAMPBELL, OF BERKELEY, CALIFORNIA.

VALVE.

1,327,984.

Specification of Letters Patent.

Patented Jan. 13, 1920.

Application filed March 27, 1918. Serial No. 225,106.

To all whom it may concern:

Be it known that I, ROBERT E. CAMPBELL, a citizen of the United States, residing at Berkeley, in the county of Alameda and 5 State of California, have invented new and useful Improvements in Valves, of which the following is a specification.

This invention relates to a valve.

One of the objects of the present invention is to provide a simple, cheaply manufactured valve for regulating the flow of water and the like, and which is so constructed that ordinary packing may be entirely eliminated. Another object of the 15 invention is to provide a spherical valve having a central passage formed therein and a stem for turning the valve to bring the central passage into or out of register with a longitudinal passage extending through 20 the valve casing. Another object of the invention is to provide a removable non-metallic valve seat, together with means for securing it within the casing. Further objects will hereinafter appear.

25 The invention consists of the parts and the construction and combination of parts as hereinafter more fully described and claimed, having reference to the accompanying drawings, in which—

30 Figure 1 is a central, vertical, longitudinal section through the valve.

Fig. 2 is a central, vertical, cross section of same, taken on the line 2—2 of Fig. 1.

Referring to the drawings in detail, A 35 indicates a valve casing, 2 the valve proper, 3 the stem, and 4 the spout of the valve. Formed interiorly of the casing is a longitudinally extending passage, one end of 40 which is enlarged, as at 5, to permit the insertion of a non-metallic member 6, such as shown. The opposite end of the passage is contracted, as at 7, and communicates with a threaded extension 8 which permits the valve casing to be screwed on the end 45 of a pipe or other suitable fitting.

Formed on the inner end of the non-metallic member is a seat 9; with which the valve 2 is adapted to engage, and formed in the housing on the opposite side of the 50 valve is a seat 10. The valve proper is preferably spherical as here shown and is provided with a central passage 11 and a recess 12 to permit it to be turned by means of the valve stem 3; the lower end of the valve

stem being provided with a square extension 13 which enters the recess, thus permitting the valve and stem to be made in two separate parts and also permitting turning movement of the stem to be transmitted to the valve. The stem otherwise extends 60 through the threaded projection 14 of the casing, on the upper end of which is formed a seat 15.

Interposed between the seat 15 and a second seat 16 formed on a collar 17 on the 65 stem is a spherical packing member 18. That is, any liquid which might pass by the seat 10 in the valve 2 might leak up around the stem and out through the cap 19 which incloses it. However, this is prevented in 70 the present instance as the spherical packing 18 employed tightly engages the seats 15 and 16, due to the pressure exerted by the screw cap 19. This spherical packing member is preferably constructed of a non- 75 metallic material, such as vulcanized rubber, fiber, or the like, and although it is subject to comparatively little wear it is obvious that any that might take place may be taken care of by merely tightening the screw 80 cap 19.

The non-metallic member 6, of which the valve seat 9 is formed, is secured in position by means of a spout 4. The inner end of the spout is provided with an extension 85 20 which fits a central passage 21 formed in the member 6. A washer 22 surrounding the extension 20 and interposed between the spout and the member 6 prevents leakage of any water that might tend to escape 90 between the valve casing and the member 6 and it also serves as a means for forcing the non-metallic member, upon which the seat is formed, against the spherical valve; pressure for this purpose being obtained 95 by providing a screw cap 23. This screw cap engages an annular shoulder 24 formed on the spout and will, therefore, when tightened, force the spout inwardly against the gasket 22 and the member, thus expanding the gasket and simultaneously forcing the member 6 against the valve 2 and preventing any leakage even though wear should take place. The screw cap 23 also has the function of permitting the spout to 100 be turned in any direction desired and locks it when thus adjusted by merely tightening the cap. This is of considerable impor-

tance as it permits the discharging stream passing through the valve to be directed as desired.

The member 6, while preferably constructed of vulcanized rubber or fiber, may be constructed of metal, if desired, but actual practice has shown that practically no wear takes place between the metallic valve 2 and the non-metallic member 6 even though considerable grit is carried by the water. The materials and finish of the other parts of the valve may be such as the experience and judgment of the manufacturer may dictate.

I wish it understood that various changes in form, proportions and minor details of construction may be resorted to within the scope of the appended claims and that I do not wish to limit myself to the specific design and construction here shown.

Having thus described my invention, what I claim and desire to secure by Letters Patent is—

1. A valve comprising a casing having a central, longitudinal passage extending therethrough, one end of said passage being enlarged, a member having a central passage formed therein adapted to be received in the enlarged portion of the casing passage, a valve seat on the inner end of said member, a spherical valve within the casing adapted to engage said seat, said valve having a central passage formed therein, means for turning the valve to bring the central passage into and out of register with the passages formed in the casing and in the insertible member, a removable spout on the casing, a resilient packing member interposed between the spout and the insertible member, and means for securing the spout on the casing.

2. A valve comprising a casing having a central, longitudinal passage extending therethrough, one end of said passage being enlarged, a member having a central passage formed therein adapted to be received in the enlarged portion of the casing passage, a valve seat on the inner end of said member, a spherical valve within the casing adapted to engage said seat, said valve having a central passage formed therein, means for turning the valve to bring the central passage into and out of register with the passages formed in the casing and in the insertible member, a removable spout on the casing, a resilient packing member interposed between the spout and the insertible member, and means for adjustably securing the spout to the casing.

3. A valve comprising a casing having a central, longitudinal passage extending therethrough, one end of said passage being enlarged, a non-metallic member having a central passage formed therein in alinement with the casing passage adapted to be received in the enlarged portion of the casing

passage, a valve seat on the inner end of the non-metallic member, a spherical valve within the casing adapted to engage said seat, said valve having a central passage formed therein, means for turning the valve to bring the central passage formed therein into and out of register with the passages formed in the non-metallic member and in the valve casing, a removable spout on the valve casing having an extension formed thereon, adapted to project into the central passage, a resilient member interposed between said extension and the non-metallic member, said spout having a passage formed therein in register with the passage in the non-metallic member, and a screw cap adapted to inclose the inner end of the spout to secure the spout to the casing and also to exert endwise pressure on the spout, the resilient member and the non-metallic member.

4. A valve comprising a casing having a central, longitudinal passage extending therethrough, one end of said passage being enlarged, a non-metallic member having a central passage formed therein in alinement with the casing passage adapted to be received in the enlarged portion of the casing passage, a valve seat on the inner end of the non-metallic member, a spherical valve within the casing adapted to engage said seat, said valve having a central passage formed therein, means for turning the valve to bring the central passage formed therein into and out of register with the passages formed in the non-metallic member and in the valve casing, a removable spout on the valve casing adapted to engage the outer end of the non-metallic member, said spout having a passage formed therein in register with the passage in the non-metallic member, a screw cap adapted to inclose the inner end of the spout to secure the spout to the casing and also to exert endwise pressure on the spout and the non-metallic member, an extension on the inner end of the spout adapted to enter the passage in the non-metallic member, and a resilient gasket interposed between the spout and the non-metallic member.

5. A valve comprising a casing having a central longitudinal passage formed therein, one end of said passage being enlarged and having a valve seat formed at the inner end of said enlargement, a spherical valve within the enlarged portion of the passage, engageable with the seat, a packing member insertible in the passage, having a valve seat formed on its inner end, engageable with the spherical valve, a central passage formed in the packing member, the outer end of said passage being enlarged, a spout insertible in the passage, said spout having an extension formed on its inner end, adapted to be received in the enlarged por-

tion of the passage formed in the packing member, and means for exerting an endwise pressure on the spout and through the spout against the packing member and the spherical valve.

6. A valve comprising a casing having a central longitudinal passage formed therein, one end of said passage being enlarged and having a valve seat formed at its inner end, 10 a spherical valve within the enlarged portion of the passage, engageable with the seat, a packing member insertible in the passage, having a valve seat formed on its inner end, engageable with the spherical valve, a central 15 passage formed in the packing member, the outer end of said passage being enlarged, a spout insertible in the passage, said spout having an extension formed on its inner end, adapted to be received in the enlarged portion 20 of the passage formed in the packing

member, means for exerting an endwise pressure on the spout and through the spout against the packing member and the spherical valve, a central passage formed in the valve, means for transmitting a turning 25 movement to the valve to bring the said passage into or out of alinement with the main central passage formed in the casing, and a resilient packing member surrounding the reduced portion of the spout and interposed 30 between the spout and the first named packing member.

In testimony whereof I have hereunto set my hand in the presence of two subscribing witnesses.

ROBERT E. CAMPBELL.
